(57) **CLAIM**

I claim the ornamental design for a gun case, as shown and described.

DESCRIPTION

FIG. 1 is a perspective view of the gun case showing my new design

FIG. 2 is the left side elevation view of the gun case.

FIG. 3 is the right side elevation view of the gun case.

FIG. 4 is the bottom view of the gun case.

FIG. 5 is the top view of the gun case.

FIG. 6 is the front elevation view of the gun case; and, FIG. 7 is the rear elevation view of the gun case.

The broken lines representing stitching are part of the claimed design.
